UNITED STATES PATENT OFFICE.

WALTER ATKINS, OF SAN FRANCISCO, CALIFORNIA, ASSIGNOR OF ONE-THIRD TO WILLIAM J. PEDLER AND ONE-THIRD TO ALBERT D. PLUGHOF, BOTH OF SAN FRANCISCO, CALIFORNIA.

CHILD'S VELOCIPED.

1,336,879.

Specification of Letters Patent. Patented Apr. 13, 1920.

Application filed December 3, 1919. Serial No. 342,088.

To all whom it may concern:

Be it known that I, WALTER ATKINS, a subject of the King of England, residing at San Francisco, in the county of San Francisco and State of California, have invented new and useful Improvements in Children's Velocipedes, of which the following is a specification.

The object of the present invention is to provide a child's velocipede, coaster or scooter, in the form of an aeroplane.

In the accompanying drawing Figure 1 is a side view of my improved velocipede, Fig. 2 as a plan view thereof; Fig. 3 is a front view thereof; Fig. 4 is a bottom plan view thereof.

Referring to the drawing, 1 indicates a base plate supported upon front and rear pairs of skate wheels 2. The outline of said base plate being made to resemble that of the body of an aeroplane so that it tapers to the rear, and upon the rear end thereof is secured a tail board 3 of greater width than the board 1, thus resembling the tail piece 25 of an aeroplane and forming a seat for the rider. Secured on the under side of the board 1 near its front end by staples 6 is a transverse shaft 7, on which are pivotally mounted brakes 8 the rear ends of which 30 slide over the ground but can be pressed by the feet of the rider into the ground, thus checking the movement of the velocipede. Upon the forward portions of the board 1 are secured as shown at 9, 10, the horizontally bent ends, of yoke-shaped standards 11 the middle portions of which are secured, as shown at 13, to the under side of an upper cross piece 14, while the intermediate portions of said standards are secured, as shown 40 at 16, to the front or rear edges of a lower cross piece 17. Said upper and lower cross

pieces 14 and 17 are of considerably greater length than the width of the board 1, so as to resemble in general appearance the upper and lower planes of an aeroplane. They are 45 connected together at their ends and at the front and rear by standards 18, said standards with the yoke shaped members 11 thus completing the resemblance to an aeroplane.

The lower portions of said standards are 50 braced to each other by front and rear braces 21. Secured centrally to the front edges of the upper and lower cross pieces 14 and 17, as shown at 22 are the ends of a bar 23 bent forwardly in the middle portion, 55 and extending forwardly from said middle portion is a bolt 24 on which is pivoted a propeller shaped vane 26. The motion of the vehicle through the air causes said vane to be rotated and gives it the appearance of 60 the propeller of an aeroplane.

In one of the cross pieces, preferably the upper cross piece, as here shown, are formed two elongated holes or slits 27 serving as hand holds for the rider of the velocipede. 65

I claim:—

The combination of a board, front and rear pairs of skate wheels on which said board is mounted, a tail board of greater width than the rear end of the first named 70 board, upper and lower cross pieces of greater length than the width of the board, iron bars the lower ends of which are secured to the board and which extend upwardly from said board and support said 75 cross pieces, an upwardly extending bar secured centrally to the front edges of said cross piece and bent forwardly in the middle, and a propeller shaped vane rotatably supported at the center of said bar.

WALTER ATKINS.
